UNITED STATES PATENT OFFICE

HERBERT "UB" IWERKS, OF BEVERLY HILLS, CALIFORNIA, ASSIGNOR TO CELEBRITY PRODUCTIONS, INC., OF NEW YORK, N. Y., A CORPORATION OF NEW YORK

DESIGN FOR A STATUETTE OR SIMILAR ARTICLE

Application filed September 30, 1931. Serial No. 41,265. Term of patent 14 years.

To all whom it may concern:

Be it known that I, HERBERT "UB" IWERKS, a citizen of the United States of America, residing at Beverly Hills, in the county of Los Angeles and State of California, have invented a new, original, and ornamental Design for a Statuette or Similar Article, of which the following is a specification, reference being had to the accompanying drawings, forming part thereof.

In the drawings,

I claim:

The ornamental design for a statuette or similar article as shown.

HERBERT "UB" IWERKS.
